UNITED STATES PATENT OFFICE.

CHARLES R. KEERAN, OF EVANSTON, ILLINOIS, ASSIGNOR TO SWANBERG MANUFACTURING COMPANY, OF CHICAGO, ILLINOIS, A CORPORATION OF ILLINOIS.

PENCIL CLIP.

Original application filed June 10, 1927, Serial No. 197,793. Divided and this application filed February 29, 1928. Serial No. 257,915.

The present invention relates to improvements in pencil clips and has for an object to provide a simple and effective method of attaching a clip to a pencil barrel. It consists in certain features and elements of construction herein shown and described and as indicated by the claims.

In the drawings:

Figure 1 is a view of a pencil embodying my invention, the upper end of the pencil being broken in section to show details of construction.

Figure 2 is a fragmentary view looking at the face side of my improved clip as it appears attached to a pencil barrel.

Figure 3 is an enlarged transverse detail section through the pencil and clip, taken as indicated at the line 3—3 on Figure 1.

This is a division of my co-pending application, Serial No. 197,793, filed June 10, 1927.

As illustrated in the drawings, the pencil is shown provided with a barrel, 10, which may be understood to be formed of any suitable material, such as wood, metal, bakelite or other molded composition.

A spring clip indicated at 11 is provided with an offset, 12, which merges into a straight tang, 13, which fits snugly in a longitudinal groove, 14, cut in the barrel, at the reduced portion, 15, extending from a shoulder, 16, to the upper end of the barrel. The groove includes a radial portion at 17 to accommodate the offset part, 12, of the clip, and to hold the clip in this position a tight retaining ring, 18, is forced onto the reduced barrel at 15 over the tang, 13, and against the part, 12. A removable sleeve, 19, holding an eraser, 20, may be fitted over the ring, 18, to provide a finish for the upper end of the pencil, the eraser being secured in the sleeve in any preferred manner, permitting it to be replaced when worn. Obviously, if desired, a merely ornamental cap (not shown) may be substituted for the sleeve, 19, or may be applied over it to keep the eraser clean when not in use.

This improved clip and method of attach-

ment to the barrel is very simple; yet effective, and may be economically made. Although I have shown and described a preferred embodiment of my invention, it is to be understood that my invention is not limited to the specific showing, but is capable of other adaptations and modifications within the scope of the appended claims.

I claim:

1. In a pencil having a shouldered body, a spring clip having an offset portion engaging the shoulder and a tang extending from the offset portion, together with a retaining ring fitted tightly around the body overlapping the tang.

2. In a pencil having a body with a reduced portion forming a shoulder, a longitudinal groove in said portion and a spring clip having an offset portion engaging the shoulder and a tang lodged in the groove, together with a retaining ring fitted tightly on the reduced part of the body overlapping the tang to secure it in the groove.

3. In the combination defined in claim 2, said shoulder having a recess connecting with the groove and adapted to receive the offset portion of the clip, and a ring being disposed on the reduced portion of the body abutting the shoulder.

4. In a pencil having a body, a spring clip therefor having a tang extending longitudinally over a portion of the body surface, a retaining ring on said body overlapping the tang for securing the clip, and a removable head sleeve slidably fitted over said retaining ring.

5. In the combination defined in claim 3, a removable head sleeve slidably fitted over the ring to abut the shoulder.

6. In a pencil having a body, a spring clip therefor having a tang extending over a portion of the body surface, a retaining ring on the body overlapping said tang and a head removably fitted over said ring.

CHARLES R. KEERAN.
